(57) **CLAIM**

We claim the ornamental design for a food chopper, as shown and described.

DESCRIPTION

FIG. 1 is a perspective view of a food chopper of the present invention;

FIG. 2 is a bottom perspective view thereof;

FIG. 3 is a top perspective view thereof;

FIG. 4 is a front view thereof;

FIG. 5 is a rear view thereof;

FIG. 6 is a right side view thereof;

FIG. 7 is a left side view thereof;

FIG. 8 is a bottom plane view thereof; and,

FIG. 9 is a top plane view thereof.

Any broken lines in the drawings are for illustrative purposes only and form no part of the claimed design.
